UNITED STATES PATENT OFFICE.

SIGMUND WURF, OF BOSTON, MASSACHUSETTS, ASSIGNOR OF ONE-HALF TO
CRESCENZO DE SIMONE, OF BOSTON, MASSACHUSETTS.

PROCESS OF INLAYING DESIGNS ON GLASS.

Application filed June 14, 1924. Serial No. 720,118.

Broadly this invention relates to glass ornamentation, but it more especially comprehends an improved method or process for inlaying a predetermined design on glass.

The principal object of this invention is to provide a simple and efficient process for inlaying a predetermined design or emblem in mother of pearl, gold clippings, or other suitable material on glass for the ornamentation of trays and the like.

Another important object of this invention is the provision of an improved process for inlaying a predetermined design or emblem on glass, one of the necessary steps in the process also providing a back ground for the design of any contrasting or desired color.

Fig. 1 is a plan view of an emblem inlaid on glass in accordance with my improved process;

Fig. 2 is a cross section on the line 2—2 of Fig. 1.

I am aware that many processes and methods have been evolved for effecting an ornamental inlaid design on glass, but these, owing to a multiplicity of steps or intricate operations and amount of time, labor and materials required have proven either too costly or for other reasons more or less unsatisfactory, and to overcome such deficiencies and to provide a simple, efficient and inexpensive process of inlaying a predetermined design on glass or the like, one of the necessary steps in the process also providing a back-ground for the inlaid design of any desired color, that I evolved the process forming the subject matter of this invention.

The various steps or operations in my process for attaining the desired object, that is, an inlaid design or emblem on glass with a back-ground of contrasting color, are as follows: first, a layer of tin foil or the like is carefully laid over the entire reverse surface of the glass to be decorated; then a pattern of card board in the form of the design or emblem is superimposed on the tin foil and the latter is then cut with a sharp knife corresponding to the form of the pattern. Though I have preferably specified card board, any suitable form of pattern may be employed according to the particular requirements.

The next step following the above operation is to remove all the tin foil except that representing the design by means of an ordinary knife or by any other suitable means, leaving a pattern on the glass in the form of the desired design or emblem 55, and border 6, when the latter is desired, after which a coat of paint 2 is applied to cover the glass 1 and the tin foil representing the design and the border. One or more coats of this paint may be applied according to 60 the particular requirements, but as the first application represents the back-ground for the design or emblem and covers all of the glass except that covered by the inlay, it may be of the desired color to contrast with 65 the inlaid portions.

When the paint 2 applied as above described has dried the remaining tin foil is removed leaving an empty or channeled design and border 6 on the glass 1. Then a 70 coat of transparent varnish 4 is applied over the whole glass including the empty design 6, after which, the recessed design or emblem is inlaid with pearls 3, the interstices between the pearls, in the present instance, being filled with gold metal clippings of color sheet 5. Of course, any suitable material or materials may be employed in lieu of those above specified according to the 75 particular requirements, such inlaid materials then being pressed into the said empty design 6, and firmly secured therein by the said transparent varnish 4. Though it is not in many instances necessary, in others it has been found expedient to cover the entire varnished surface and the inlaid design with a sheet of tin or gold foil 5, and in 80 many cases this sheet may be additionally utilized to at the same time supply part of the inlaid design by filling in the interstices between the pearls or other inlaid material.

From the foregoing it will be apparent that I have evolved a simple, inexpensive, labor-saving process of great practicability 100 for the ornamentation of glass by effecting inlaid designs or emblems 7 thereon, and although certain particular steps and materials have been specified, it is to be understood that the same may be modified or varied within the scope of the appended claims 105 without departing from or sacrificing any of the principles of this invention.

Having now described my invention, what I desire to secure by Letter's Patent is as set forth in the following claims:

- 5 1. A process for the ornamentation of glass consisting in building up the reverse surface of the glass by the application of a coating of hardening fluid and providing recesses in said coating in the form of the desired design, subjecting the recesses to an application of transparent material, inlaying the said recesses with pearls or the like and subjecting the inlaid material to pressure.
- 10 2. A process of ornamenting glass by inlaying a design thereon, consisting of superimposing on the reverse surface of the glass tin foil in the form of the design, covering the glass and foil with a coating of hardening material, removing the tin foil to provide recesses, applying a coating of transparent adhesive fluid over the entire surface including the recesses, inlaying the recesses, and subjecting the inlaid material to sufficient pressure to embed the same in said recesses and transparent material.
- 15 3. A process of ornamenting glass by inlaying a design thereon, consisting of building up the reverse surface of the glass by

the application of a coating of hardening fluid, a pigment associated with said coating for providing a background for said design, providing recesses in said coating in the form of the desired design, subjecting the recesses to an application of transparent material, inlaying the said recesses, and subjecting the inlaid material to pressure.

- 20 4. A process of ornamenting glass by inlaying a design thereon, consisting of building up the reverse surface of the glass by the application of a coating of hardening pigmented fluid to provide a background for said design, providing recesses in said coating in the form of the desired design, subjecting the recesses and the pigmented material to an application of transparent material, inlaying the said recesses, applying a color material over the pigmented surface and the inlaid material, subjecting the inlaid and color material to pressure to embed the color material in the interstices in the inlaid material, said color material also forming a backing to encase the inlaid emblem and pigmented material between said color material and glass.
